CLAIM

The ornamental design for a drawer part, as shown and described.

DESCRIPTION

FIG. 1 is a top perspective view of a drawer part;

FIG. 2 is a top view thereof;

FIG. 3 is a front view thereof;

FIG. 4 is a right side view thereof;

FIG. 5 is a left side view thereof;

FIG. 6 is a rear view thereof; and,

FIG. 7 is a bottom view thereof.

It is noted that the portions of the drawings indicated with broken lines illustrate environmental structure and form no part of the claimed design.
